UNITED STATES PATENT OFFICE.

GUSTAVO TRIFARI, OF NEW YORK, N. Y., ASSIGNOR TO TRIFARI, KRUSSMAN & FISHEL, INC., OF NEW YORK, N. Y.

DESIGN FOR A HANDLE FOR A FINGER-NAIL FILE OR SIMILAR TOILET ARTICLES.

Application filed October 6, 1926. Serial No. 19,254. Term of patent 8½ years.

To all whom it may concern:

Be it known that I, GUSTAVO TRIFARI, a citizen of the United States, residing in the city of New York, county of New York, and State of New York, have invented a new, original, and ornamental Design for a Handle for a Finger-Nail File or Similar Toilet Articles, of which the following is a specification, reference being had to the accompanying drawing, forming part thereof.

I claim:

The ornamental design for a handle for a finger-nail file or similar toilet articles, as shown.

GUSTAVO TRIFARI.
